CAR COUPLER

William J. Metzger, Cleveland, Ohio, assignor to
 National Malleable and Steel Castings Company, Cleveland, Ohio, a corporation of Ohio

Application November 16, 1938, Serial No. 240,679

5 Claims. (Cl. 213—151)

This invention pertains to car couplers and particularly to improvements in the type of coupler disclosed in Bazeley application Serial No. 53,612, filed December 5, 1935, now issued as Patent No. 2,178,062, Oct. 31, 1939.

An object of the invention is to improve the operation of the coupler during uncoupling movements so as to eliminate binding in the contour such as would retard separation of the couplers.

The particular problem involved and the solution thereof which constitutes the present invention may be more clearly understood from the following description and drawings, in which:

Figure 1 is a view in horizontal section through a pair of couplers embodying my invention.

Figure 2 is a diagram illustrating the longitudinal and lateral movement, during uncoupling, of couplers with and without my invention.

Figure 3 is a view of the contour of a pair of couplers as they were made previous to my invention.

Figure 4 is a view of the contour of a pair of couplers embodying my invention; and

Figure 5 is a plan view of a knuckle showing the old and new contours.

In Fig. 1 there is shown a pair of couplers in coupled position each having a knuckle 1 pivoted at 2 and adapted to be held rigid with the coupler head 3 by means of a lock 4. The couplers are mounted on the car structure in the usual manner so as to allow some pivotal movement of the coupler. The knuckle noses 12 are shown interlocked, and the buffing face 7 of each knuckle, which face is substantially perpendicular to the longitudinal axis of the coupler, is engaged with the buffing face 8 of the opposing coupler head. Adjacent face 7 the contour of each knuckle slopes rearwardly, as at 9, and merges into the contour of the knuckle nose 12. The knuckle on the coupler at the right of Fig. 1 is shown in dot-dash lines in open position. Each coupler is formed at one side with a recess 5 and at the other side with a projection 6 adapted to enter the recess of the opposing coupler to guide the two into coupled position.

It has been found in tests of full size couplers, of the type shown in the aforesaid Bazeley application, that separation of two couplers is sometimes retarded by reason of the contours binding in each other. This condition is illustrated in Fig. 3, which shows two couplers with old contours partially separated. Coupler A is locked with its knuckle 10 held rigid with respect to its

coupler head, and in coupler B the lock has been raised to permit knuckle 11 to swing outwardly to effect uncoupling. In the position shown in Fig. 3, which I call the critical position, the 5 knuckle 10 is in contact with the tail 13 of knuckle 11 at point 14, which is substantially at the juncture of buffing face 7 and rearwardly sloping surface 9; at the same time the knuckle noses are in contact at point 15. Since the 10 knuckles are in effect wedged into contact at points 14 and 15, further movement of knuckle 11 about its pivot is practically impossible. Knuckle 11 and its associated coupler cannot 15 rotate about point 14 since there are overlapping portions of the noses of the knuckles, as shown by the arc a—a drawn through point 15 with point 14 as a center. The metal at 16, between arc a—a and the outer face of the nose of knuckle 10, it will be observed, overlaps metal at 17 between arc a—a and the outer face of 20 the nose of knuckle 11, hence the aforesaid movement about point 14 cannot take place.

The only way the two couplers can separate 25 is by movement generally in the direction of the line x—x, which is drawn tangent to the knuckle noses at point 15. However, line x—x is almost perpendicular to the longitudinal center line c—c of the coupler, and, therefore, considerable lateral movement between the couplers would have to take place upon very little longitudinal separation thereof. The friction between the contacting surfaces may be very great due to the wedging engagement of the two knuckles, and separation thereof is sometimes retarded to such 30 extent as to make this condition objectionable.

Since the principal feature of this type of coupler is the tight contour through which slack is eliminated in coupled couplers, the aforesaid difficulty had to be overcome, if at all, without 35 loosening the contour in such a manner as would destroy the advantage of the tight contour. I have found that by increasing the relative lateral separation of the couplers and increasing the outward pivotal movement of the knuckle before the critical point is reached, the noses of the knuckles can readily slide past each other 40 and along a line tangent to the noses at the point of contact that is at a substantially lesser angle to the longitudinal center line of the coupler than in the couplers as they were before the difficulty was discovered. In my invention there is no possibility of one knuckle becoming wedged 45 in the contour of the opposing knuckle during 50 the uncoupling operation.

In Fig. 5 the old and the new contours are superimposed on the same knuckle, the old being in dot-dash lines and the new in solid lines. It will be seen that metal has been added to and removed from the former knuckle tail pulling face. I have found that the new contour, formed by changing the $3\frac{1}{2}$ " radius as shown in Fig. 5 to 10", and drawing the latter tangent to the $2\frac{1}{2}$ " radius and also tangent to a line that is parallel to the dot-dash line representing the former construction but spaced $\frac{1}{8}$ " therefrom, will increase the amount of lateral separation of the couplers as well as the amount of outward pivoting of the knuckle before the critical point aforementioned is reached so as to effect smooth uncoupling. The other dimensions of the knuckle face and nose remain the same as on the old knuckle.

Referring to Fig. 4 in which knuckle 1 of coupler A' is locked while knuckle 1 of coupler B' is unlocked, the effect of the new contour is clearly shown. Movement of the knuckle of coupler B' up to its position shown has taken place smoothly, and in this position the two knuckle noses are in contact at point 15' while the tail of the knuckle of coupler B' is in engagement with the knuckle of coupler A' at point 14', which again is substantially at the juncture of buffing face 7 with rearwardly sloping surface 9. By scribing an arc a'-a' through point 15', using point 14' as a pivot point, it will be observed that the arc does not pass through any portion of the nose of knuckle A' or B'. It will be noted that the distance between points 14' and 15' is at least as great as the distance from point 14' to any other point on the contour of the nose of the knuckle of coupler A'. Moreover, the distance from 14' to 15' is no greater than the distance from 14' to points on the contour of the nose of the knuckle of coupler B' adjacent point 15'. Therefore, neither knuckle will tend to cut into the nose of the other knuckle when uncoupled further. The line x'-x' drawn tangent to the knuckle noses at the point of contact 15' is now at a substantially smaller angle to the longitudinal center line c'-c' and by reason thereof, the knuckles can be easily and smoothly moved past each other to uncoupled position. It will be noted that during the process of uncoupling it is the purpose of the new contour to first produce a greater lateral displacement of the couplers than provided by the old contour, and after a sufficient separation has been effected, the opening knuckle is permitted to pivot outwardly so as to reach the position shown in Fig. 4. Both the greater initial separation of the couplers and the increased pivotal movement of the opening knuckle contribute to produce smooth uncoupling of couplers constructed in accordance with my invention.

To illustrate graphically the relative movement of the couplers during the uncoupling operation, there is shown in Fig. 2 the path of the center of the knuckle pivot pin, of the coupler having its lock lifted to permit opening of its knuckle, as the couplers are uncoupled. The full line represents the path of the pin of a coupler having a new contour and the dot-dash line represents the same for a coupler having the old contour. Lateral movement of the couplers is represented by distances perpendicular to the base line, while longitudinal movement is represented by distances along the base line. Starting at point F, which represents the position of

the pin when both knuckles are closed, it will be observed that at the start of uncoupling, the lateral separation of the couplers is the same for both the old and new contours. However, as longitudinal movement progresses, the new contour line passes above that of the old, thus showing that a greater lateral separation occurs. With the old contour the critical point is at J which corresponds to the position of the knuckle as shown in Fig. 3. It will be noted that immediately after point J the lateral displacement of the old contour couplers increases very rapidly, and it is this greater lateral movement necessary upon small longitudinal movement which retards uncoupling. Now referring to the new contour line it will be seen that, at the time the old contour knuckles are at the critical point J or as shown in Fig. 3, the new contour knuckles are moving past each other in a direction substantially parallel to the longitudinal movement of the couplers, and no point that might be critical is reached until point H. However, at point H the knuckles are in the position as shown in Fig. 4, and as has been previously explained, further disengagement of the couplers may be readily accomplished. With the new contours the lateral displacement of the couplers is more even throughout the uncoupling period than with the old contours, and more nearly approaches a straight line movement.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

- 40 1. A car coupler having a pivotally mounted knuckle shaped to cooperate with the knuckle and coupler face of another coupler of similar shape in tight fitting engagement, with the inner surfaces of the knuckles interlocked with each other, and with the knuckle buffing faces engaging the opposing coupler buffing face, said first named knuckle having a rearwardly extending tail, said tail having a surface adapted to engage the buffing face of the knuckle of said opposing coupler upon pivotal movement of said first named knuckle during uncoupling, said surface being of such configuration that during uncoupling said couplers will be moved laterally relative to each other an amount sufficient to prevent the knuckle of one coupler from binding between the knuckle nose and tail of an opposing coupler, the contour of said tail being comprised of a 1" radius centered $\frac{1}{8}$ " from the center line of the coupler on the same side thereof as the pivot for said knuckle, a $2\frac{1}{2}$ " radius tangent to said 1" radius and centered $1\frac{7}{8}$ " from the coupling line of said coupler at a point below the nose of the knuckle, a 10" radius tangent to said $2\frac{1}{2}$ " radius centered $\frac{3}{8}$ " from said coupling line on the side thereof opposite to the centers of said first named radii, and a line tangent to said 10" radius and positioned at an angle of 37° to the center line of the coupler.
- 45 2. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longi-
- 50 3. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longi-
- 55 4. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longi-
- 60 5. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longi-
- 65 6. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longi-
- 70 7. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longi-

tudinal center line of said coupler and a surface adjacent said buffing surface sloping rearwardly therefrom toward the nose of said knuckle, the inner surfaces of the noses of said knuckles being in engagement upon pivotal movement of said first named knuckle during uncoupling of said couplers, said first named knuckle having a tail with a surface adapted to engage the opposing knuckle substantially at the juncture of said sloping and buffing surfaces of said opposing knuckle during uncoupling of the couplers, said tail surface having a configuration such that upon the said engagement thereof with said opposing knuckle the distance from said point of engagement to the point of contact between said knuckle noses is at least as great as the distance from said point of engagement to any other point on the contour of the nose of said opposing knuckle, and the configuration of said tail surface being such that during separation of two couplers there will be free rolling contact between said tail surface and the buffing surface of the opposing knuckle.

3. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longitudinal center line of said coupler and a surface adjacent said buffing surface sloping rearwardly therefrom toward the nose of said knuckle, the inner surfaces of the noses of said knuckles being in engagement upon pivotal movement of said first named knuckle during uncoupling of said couplers, said first named knuckle having a tail with a surface adapted to engage the opposing knuckle substantially at the juncture of said sloping and buffing surfaces of said opposing knuckle during uncoupling of the couplers, said tail surface being constructed and arranged to separate said couplers laterally relative to each other during uncoupling, such an amount that upon the aforesaid engagement the distance from said point of engagement to the point of contact between said knuckle noses is at least as great as the distance from said point of engagement to any other point on the contour of the nose of said opposing knuckle, and the configuration of said tail surface being such that during separation of two couplers there will be free rolling contact between said tail surface and the buffing surface of the opposing knuckle.

4. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longitudinal center line of said coupler and a surface adjacent said buffing surface sloping rearwardly therefrom toward the nose of said knuckle, the inner surfaces of the noses of said knuckles being in engagement upon pivotal movement of said first named knuckle during uncoupling of said couplers, said first named knuckle having a

tail with a surface extending diagonally rearwardly and terminating with a lock engaging surface extending parallel to the longitudinal axis of said coupler, portions of said tail surface forwardly of said lock engaging surface being adapted to engage the opposing knuckle to force the couplers laterally apart, and said tail surface being engageable with the opposing knuckle substantially at the juncture of said sloping and buffing surfaces of said opposing knuckle during uncoupling of the couplers, said tail surface having a configuration such that upon the said engagement thereof with said opposing knuckle the distance from said point of engagement to the point of contact between said knuckle noses is no greater than the distance from said point of engagement to points on the nose of said first named knuckle adjacent the point of engagement between said knuckles, and the configuration of said tail surface being such that during separation of two couplers there will be free rolling contact between said tail surface and the buffing surface of the opposing knuckle.

5. A car coupler having a pivotally mounted knuckle shaped to cooperate with the knuckle and coupler face of another coupler of similar shape in tight fitting engagement, with the inner surfaces of the knuckle noses interlocked with each other, said knuckle having a buffing surface substantially perpendicular to the longitudinal center line of said coupler and a surface adjacent said buffing surface sloping rearwardly therefrom toward the nose of said knuckle, the inner surfaces of the noses of said knuckles being in engagement upon pivotal movement of said first named knuckle during uncoupling of said couplers, said first named knuckle having a tail with a surface extending diagonally rearwardly and terminating with a lock engaging surface extending parallel to the longitudinal axis of said coupler, portions of said tail surface forwardly of said lock engaging surface being adapted to engage the opposing knuckle to force the couplers laterally apart, and said tail surface being engageable with the opposing knuckle substantially at the juncture of said sloping and buffing surfaces of said opposing knuckle during uncoupling of the couplers, said tail surface having a configuration such that upon the said engagement thereof with said opposing knuckle the distance from said point of engagement to the point of contact between said knuckle noses is at least as great as the distance from said point of engagement to any other point on the contour of the nose of said opposing knuckle, and the configuration of said tail surface being such that upon the said engagement thereof with said opposing knuckle the distance from said point of engagement to the point of contact between said knuckle noses is at least as great as the distance from said point of engagement to any other point on the contour of the nose of said opposing knuckle, and such that the distance from said point of engagement to the point of contact between said knuckle noses is no greater than the distance from said point of engagement to points on the nose of said first named knuckle adjacent the point of engagement between said knuckle noses, and the configuration of said tail surface being such that during separation of two couplers there will be free rolling contact between said tail surface and the buffing surface of the opposing knuckle.

WILLIAM J. METZGER.
